UNITED STATES PATENT OFFICE.

JOHN J. KNAPP, OF RICHLAND, WEST VIRGINIA.

LOCK.

SPECIFICATION forming part of Letters Patent No. 299,805, dated June 3, 1884.

Application filed March 17, 1884. (No model.)

To all whom it may concern:

Be it known that I, JOHN J. KNAPP, a citizen of the United States, residing at Richland, in the county of Greenbrier and State of West Virginia, have invented a new and useful Lock, of which the following is a specification, reference being had to the accompanying drawings.

This invention has relation to improvements in door and other locks; and it consists in the novel construction and arrangement of parts, as will be hereinafter fully described, and particularly pointed out in the claim.

Figure 1 is a vertical longitudinal sectional view showing the internal mechanism of the lock in elevation, and Fig. 2 is a perspective view of the spring for preventing the key from falling out of the key-hole and operating the dog that holds the bolt to its adjustments.

Referring by letter to the accompanying drawings, *a* designates the lock-case; *b*, the bolt; *c*, the pivoted dog that holds the bolt to its adjustments; *d*, the guide-stud for the bolt; *e*, the spring that holds the key in the key-hole and prevents it from falling out, and at the same time bears against the short arm *f* of the pivoted dog to cause it to appropriately engage the bolt to hold it either sprung or withdrawn, as the case may be. The spring-lever *e* is made of spring-wire coiled at *h*, to form a bearing and furnish the necessary tension to operate its arms *i* and *k*, which extend at right angles from the coiled tension-bearing *h*. The arm *k* of the spring *e* is provided near its free end with a downward bend, *l*, which, when the spring is in place on the fulcral stud *m*, bears against the lower end of the key-guard and holds the key in the key-hole, and not only prevents it from falling out, but holds it in a normal position after it has

been turned to throw the bolt, ready to throw the bolt in either direction. The arm *i* of the spring-lever bears against the short arm of the dog *c* and holds it in engagement with the bolt, so that the spring-lever *e* has a triple function. The stop or pin *n* prevents the spring from obstructing the key-hole when it is desired to insert and remove the key. The pressure of the bend on the key-guard is sufficient to hold the key in place, but at the same time permits it to be designedly removed when necessary.

The device is cheap and simple, and is efficient for the purposes for which it is intended. The bend in the horizontal arm of the spring-lever does not interfere with the turning of the key to throw the bolt, as the spring yields to the lower end of the guard when the key is turned.

Having thus fully described my invention, what I claim as new, and desire to secure by Letters Patent of the United States, is—

In a lock, the combination, with the bolt and pivoted dog engaging the bolt, of the spring-lever having the coil tension-bearing secured upon a fulcrum-post within the lock-case, and having one of its arms engaging the short arm of the pivoted dog, and the other arm provided with a bend for engaging the lower end of the key-guard, and a stop-pin for preventing the latter arm from obstructing the key-hole, substantially as specified.

In testimony that I claim the foregoing as my own I have hereto affixed my signature in presence of two witnesses.

JOHN J. KNAPP.
